(57) **CLAIM**

The ornamental design for a split shock mount, as shown and described.

DESCRIPTION

FIG. 1 is a front perspective view of a split shock mount showing the new design;

FIG. 2 is a rear perspective view of the split shock mount of FIG. 1;

FIG. 3 is a front view of the split shock mount of FIG. 1;

FIG. 4 is a rear view of the split shock mount of FIG. 1;

FIG. 5 is a top view of the split shock mount of FIG. 1;

FIG. 6 is a right side view of the split shock mount of FIG. 1;

FIG. 7 is a bottom view of the split shock mount of FIG. 1;

and,

FIG. 8 is a left side view of the split shock mount of FIG. 1.

The difference in shading in the figures indicates a contrast of appearance and does not depict any particular color, texture, or material.

The broken lines showing of the remainder of the split shock mount is for environmental purposes only and forms no part of the claimed design.

1 Claim, 2 Drawing Sheets
